HOSTESS TRAY

Miroslav Kochman, 34—43 Crescent St.,
Long Island City, N.Y.

Filed Aug. 23, 1965, Ser. No. 86,673

Term of patent 14 years

(Cl. D44—10)

Fig. 1

Fig. 2

FIG. 1 is a perspective view of a hostess tray showing my new design, in closed condition; and

FIG. 2 is a perspective view, on a slightly reduced scale, in open condition.

The bottom of the tray is substantially plain and unornamented.

I claim:

The ornamental design for a hostess tray, as shown and described.
